SIGN ANNOUNCING APPARATUS

Jules Lüthi, Birsfelden, Switzerland

Application July 26, 1935, Serial No. 33,319
In Switzerland August 15, 1934

6 Claims. (Cl. 40—52)

This invention relates to an apparatus designed and adapted to advertise signs of any kind. It may be used most advantageously for the purpose of advertising orderly well readable and visible signs as figures and words, for instance the arrival and departure of trains in station yards, the checking numbers in banks or post-offices, ordinals in concert- and music-halls, scores in sporting competitions, exchange-lists etc. Other objects and advantages appear as the description progresses.

The nature of the invention and its distinguishing features and advantages will appear when the following specification is read in connection with the accompanying drawings, in which is shown a selected embodiment of it.

Fig. 1 is an elevation of a double-faced apparatus for numbers of three figures, actuated by electrical motor in connection with tele-controller, the front lid being taken off.

Fig. 2 is a plan view of the same without the top lid.

Fig. 3 is a vertical sectional view taken on the line A—A of Fig. 2.

Fig. 4 represents a detail of the driving appliance.

Fig. 5 is a diagram of electrical connections.

Fig. 6 is a top plan view of an apparatus advertising simultaneously on six faces.

The sign-announcing apparatus comprises thirty-three similar rods lying one over another, whereof eleven are marked A₀₀, A₁, A₁ up to A₉, further eleven are marked B₀₀, B₁, B₁ up to B₉ and another eleven C₀₀, C₁, C₁ up to C₉. The rods marked A and the rods marked B are forming the upper group I of twenty-two rods, while the rods marked C, eleven only in number, are forming the lower group II. The rods of group I are bearing on the rail-bar 10 and the group II glides between the rail-bars 11 and 12. The rail-bars 10, 11, and 12 are well fastened to the struts 13 forming part of the box frame. The rods are, all thirty-three of same, provided with two corresponding slots 14 and 15 as shown in Fig. 2 through which are passed the studs 16 and 17, the latter bolted into the bars 10, 11, and 12, being the guides for group I and II. Each rod of the group can be moved axially by itself or together with one or several others simultaneously as far as the slots 14 and 15 run. Further each rod of the group I and II bears two sign-boards D bent at an angle of 90° and connected to the

rod each by means of two links 18 forming joints. The links 18 are subjected to the action of the springs 19, which are securing the sign-

boards in their positions relatively to the rod. The whole thirty-three rods are thus bearing sixty-six sign-boards D arranged in six ranges of eleven sign-boards placed one behind another, whereof the upper group of rods I comprises the ranges III, IV, V, and VI and the lower group II the ranges VII and VIII. According to the order in which the figures must be presented on both faces of the apparatus, the corresponding ranges of sign-boards are placed diagonally on the rods. 5 This means that the rod A₀₀ is connected to the sign-boards D₀₀ of range III and D₀₀ of range IV, the second rod B₀₀ to the sign-boards D₀₀ of range V and D₀₀ of range VI; the rod A₁ to the sign-boards D₁ of the ranges III and IV; the rod 10 B₁ to the sign-boards D₁ of the ranges V and VI and so on. On the rods of group II, the lower rod C₀₀ is connected to the sign-board D₀₀ of the ranges VII and VIII, the rod C₁ to the sign-board D₁ of the ranges VII and VIII and so on. 15 The ranges VII and VIII showing the medium figure of the number, they are accordingly disposed opposite to one another. The first sign-board D₀₀ of every range doesn't bear any sign, the second, D₀ is marked 0, D₁ marks 1 . . . and 20 finally D₉ shows the figure 9. The buttresses E, strongly secured to the box-frame 13, limit the outmost position of the sign-boards for every range. The whole mechanism is well protected and closed up in the box housing of which 20 is 25 the bottom, 21 the lid, 22, 23, 24, and 25 the side-walls. 24 and 25 are the front-parts of the box with three openings F in each of them, namely F_{III}, F_{VII} and F_{VI} in 24, F_V, F_{VIII} and F_{IV} in 25. 30

In order to make quite clear the working of the sign-announcing apparatus, the operating of the parts above described may be mentioned here. For instance by pushing the rod C₉ of group II in the direction of the arrow head shown in Fig. 2 35 the two sign-boards D₉ of range VII and VIII connected with this rod are moved in the same direction until they are deviated, knocking the buttresses E_{VII} and E_{VIII} respectively, whereafter the sign-boards continue their movements 40 in directions perpendicular to the direction of the rod and perpendicular to their own planes. The rod has to be pushed on until the sign-boards get in slight contact with the front parts 24 and 25. 45 The sign-boards are bearing the marks "9", 50 which appear now in the openings F_{VII} and F_{VIII}.

During the motion of translation of the sign-boards, the connecting links 18 had to oscillate on their pins against the action of the springs 19. 55

If the rod **C9** is now brought back to its initial position, the links **18** are compelled by the springs **19** and swing back, taking back the sign-boards **D9** as well along the rod and into their 5 ranges VII resp. VIII. Every sign-board can be operated in this manner, brought to appear in its opening and be taken back to its place in the corresponding range. The sign-boards **D9** of each range being farthest off the front walls, they 10 require for their operating a longer motion of the supporting rods than the outmost sign-boards **D00**.

According to the disposition chosen in this embodiment of the invention, the group of rods 15 **IB** operates the ranges of sign-boards III and IV placed in proximity of the first openings on the left of each front wall; the group **II C** operates the ranges VII and VIII in proximity of the medium openings **F VII** and **F VIII**, and the 20 group **IA** operates the ranges V and VI in proximity of the openings **F V** and **F VI**. In order to advertise the number 125 for instance, the following rods have to be moved: the first figure being 1, the rod **A1** brings the sign-boards **D1** 25 into appearance in **F III** and **F IV**; rod **C2** operates the sign-boards **D2** appearing in **F VII** and **F VIII** and rod **B5** effects the appearance of the sign-boards **D5** in the openings **F5** and **F VI**. The rods may be actuated simultaneously, so 30 that the number 125 appears at once on both front-walls together. The sign-boards **D00** bearing no signs can be used as blinds for the openings **F**. The rods are secured in their positions of readiness and of use respectively by 35 means of a locking device comprising for each rod a lock bar **G** swinging on the pivot **26** bolted to the rod, the lock bar being in connection with a spring **27**, a pawl **H** moving on the pivot **28** under compulsion of a spring **29** and blocking up 40 the lock bar by engaging the heads they are both provided with and finally a solenoid **J** actuating the pawl **H**. The lock bars are notched; the slot and crank **L**, described particularly later on, thus can catch in the notch and actuate the rod. As 45 has been described formerly, the rods have to move for different length of spaces varying from a minimum space for the rods operating the sign-boards **D00** to a maximal space for the rods operating the sign-boards **D9**. Accordingly the 50 notches in the lock bars **G** must be of varying lengths, of which the shortest corresponding to the rods supporting sign-boards **D9** and the widest corresponding to the rods supporting sign-boards **D00** are shown in Fig. 2. A single locking device 55 is shown in Figures 1 and 2 in order to avoid complicating of the drawings. Locking bars and pawls are arranged symmetrically in the apparatus; but for the solenoids being more voluminous, they are placed in several vertical ranges accordingly. The Fig. 2 shows the initial position of the locking parts; when unlocked, the locking bars **G**, under compulsion of the springs **27**, swing over 60 into the working position **IX** shown in dot and dash lines in Fig. 2. This occurs only when the 65 pawl **H** releases the locking bar, lifted by the core of the solenoid **J** actuated electrically.

The rods are in their turn operated by a driving device comprising an electrical motor not shown in the drawings, a crank disc **K** driven by this 70 motor and provided with a crank pin **30** engaged in the slot **31** of the crank **L**, guided in corresponding slots of the rail bars **10**, **11**, and **12**. One revolution of the crank disc **K** determinates one double lift of the slot and crank **L**. The 75 ratio of gearing between the motor and the crank

disc is chosen in order to obtain f. i. thirty revolutions per minute for the latter. The pin **32** fastened in the slot and crank **L** actuates the commutator **33** of the solenoid circuit. The initial position **X** of the slot and crank **L** is 5 shown in dot and dash lines in Figs. 1 and 2. By means of a special controlling appliance described further on it is possible to have the crank disc **K** effectuating the one revolution required and the commutator **33** to connect the corresponding solenoids **J** of which the rods have to be moved in order to realize a chosen advertisement. For instance the rod **A00** has to be moved on. The motor drives the crank disc **K** for one revolution and the slot and crank **L** leaves its initial 15 position **X**, moving forwards; reaching the end of this first stroke, **L** operates the commutator **33** by means of the pin **32** and thus the circuit of the solenoid **J00** is closed. The solenoid removes the pawl **H00** and the corresponding spring 20 **27** swings the lock bar **G00** in its working position parallelly to the rod **A00**. The revolution of the crank disc **K** going on, the slot and crank **L** moves on its backward stroke back to the initial position **X** but it takes along on this stroke the 25 rod **A00**, the lock bar of which is engaged with **L** by its notch. If more than one lock bar has been released by the solenoid and has come into its working position, six f. i. **L** gets engaged with them and pulls all the corresponding rods together. A second revolution of the crank disc **K** 30 cancels the advertisement: on the forward stroke of **L**, the rods are altogether moved back to the initial position until the ends of the slots **14** and **15** come to bear against the studs **16** and **17**. **L** 35 continues its stroke and pushes on the sloped ends of the notches in the lock bars **G**, provoking the latter to rotate on the axis **26** and to swing back until caught by the pawls **H**. The backward stroke of the slot and crank can operate a new advertisement, if another set of solenoids have been pre-engaged on the controller. The cancelling of an advertisement and the setting of a new one require a single rotation 40 of the crank disc **K**.

This single rotation of said crank disc **K** driven by the motor **38** is secured by the stopping device shown in Fig. 4. In the notch **34** cut into the rim of the crank disc clutches a head **36** of the lever **35**, the lever **35** being under compulsion 50 of a spring **37** and locked in this position by a pawl **51** of a servo **39**. One end of lever **35** is connected with the main commutator controlling the motor **38**. When excited, the servo **39** releases the lever **35** and moves it to the left, disengaging as well the clutch **36** and simultaneously operating the main controller **40**. Thus the motor **38** starts and drives the crank disc **K**, but after a complete revolution of the latter the head **36** catches again into the notch **34** and 55 stops the disc **K** as well as the motor, a friction clutch being the connecting link between them.

The diagram of the electric connections is shown in Fig. 5, wherein **38** is the motor, **39** the servo operating the main controller **40**. The commutator **33**, referred to in Figs. 1 and 2, operates the solenoids **J**. **41** are incandescent lamps illuminating the transparent sign-boards fixed up in the apparatus box between the rail bars **10** and **11** (Fig. 1), while **42** designates the main commutator and **43** an intermediate commutator in the lamp circuit. The commutator **43** is operated by the lever **35** (Fig. 4) like the main controller **40**. **44** indicates a transformer and **45** the controlling board on which the signs to 75

be advertised have to be selected. The main leads M and N, supplying f. i. alternating current of 220 volts, are directly connected in 46 and 47 on the primary coil of the transformer 44 and branched off to the motor, O directly and P over the main controller 40. The secondary side of the transformer with a tension of four volts f. i. is connected from the pole 48 over the line Q and the commutator 33 to the solenoids J, while the line R connects the pole 49 with the controlling board 45, presenting in three ranges of eleven signs 00, 0, 1 . . . 9 each the ends of connecting lines 5, connecting them with the corresponding solenoids. A shunt rail with a contact lever 50 enables the operator to close the solenoid circuit of any range according to the notice to be advertised. A branch connection Q1 branches off the pole 49 to the servo 39, communicating over the line R1 with the contact lever 50 of the digit range on controlling board 45, this contact lever 50 being combined with a timed commutator. The lead Q is further branched off in 33, the lead R in 42, Q2 and R2 forming the lamp circuit.

25 The apparatus having to advertise the figure 125 for instance operates as follows: the contact lever 50 of the first range on controlling board 45 be placed by the operator on the contact 1, the said lever of the second range on contact 2 and finally the same of the third range (digit range) on contact 5, latter actuating simultaneously the timed commutator. The circuit of the servo 39 thus being closed, the pawl 51 is released and clutches the lever 35 off, actuating as well the main controller 48 and the commutator 43 of the lamp circuit. The motor starts and drives the crank disc K with the slot and crank L, by which the commutator 33 is operated and closes the circuit of the solenoids J. The lock bars G released by the corresponding solenoids clutch with the slot and crank L and are taken along by the same together with the rods on which they are fastened.

30 The sign-announcing apparatus according to the invention presents the advantage that it allows the operating of one or more announcing boards by a single driving appliance, thus simplifying the construction and reducing the dimension of the housing. The signs to be shown appear directly in the show openings and are readable at any reasonable distance.

35 The electrical driving appliance may as well be substituted by a hand operated device, wherein the solenoids could be replaced by hand operated keys. Further the rod groups might be arranged in a vertical position if necessary and advantageous, as it is the case on railway-stations where several wordy texts disposed one below another have to be announced. If the announcing boards must be visible from any direction, a hexagonal

form of the housing as shown in Fig. 6 may be chosen. In such a case, six complete and similar groups of sign-board mechanisms are required, a single one being driven by the driving appliance, whereas the rods of the five remaining groups are 5 connected by a lever system to the directly driven rods or linked up chainlike. The apparatus may be adapted for any use.

Having thus described this invention, what I claim and desire to secure by Letters Patent is:

1. A sign announcing apparatus comprising in combination at least one rod, a driving appliance adapted to axially displace said rod first in one direction and then in the other direction, at least one sign board movably mounted on and displaceable with said rod, and a buttress in the path of movement of said sign-board out of its plane of movement during the displacement of said rod in one direction and to guide it back into its initial position during the displacement of said rod in 20 the other direction.

2. In a sign announcing apparatus as specified in claim 1, at least one spring adapted to be compressed by the deflection of the sign board during the displacement of the rod in one direction and to 25 press said sign board back into the initial position during the displacement of said rod into the other direction.

3. A sign announcing apparatus as specified in claim 1 in which several rods and sign boards are 30 employed, said rods being arranged in groups and said sign boards disposed in rows perpendicularly to said group of rods.

4. A sign announcing apparatus as specified in claim 1 in which a plurality of rods and sign 35 boards are employed, said rods being arranged in groups and said sign boards disposed in rows perpendicularly to said groups of rods, sign boards bearing identical signs being disposed on both sides of said rod groups and adapted to appear 40 simultaneously at both sides of the apparatus in the same order.

5. A sign announcing apparatus as specified in claim 1 in which a plurality of rods and sign 45 boards are employed said rods being arranged in several groups linked up together in optional position and driven by a simple driving appliance, one group of rods transmitting its motion to the other groups.

6. In a sign announcing apparatus as specified 50 in claim 1 wherein a plurality of rods are employed directly controlled by the driving appliance, a sign selecting appliance comprising a plurality of sign contacts, and a rod locking system adapted to cooperate with said contacts to lock the rods 55 carrying the sign boards bearing the selected signs so that these boards are displaced and appear in the apparatus.

JULES LÜTHI. 60
